UNITED STATES PATENT OFFICE.

WILLIAM B. RISDON, OF TRENTON, NEW JERSEY, ASSIGNOR TO THE
AMERICAN SAW COMPANY, OF NEW YORK, N. Y.

SAW-TOOTH.

SPECIFICATION forming part of Letters Patent No. 337,083, dated March 2, 1886.

Application filed October 9, 1885. Serial No. 179,439. (No model.)

To all whom it may concern:

Be it known that I, WILLIAM B. RISDON, of Trenton, in the county of Mercer and State of New Jersey, have invented a new and useful Improvement in Insertible Saw-Teeth, of which the following is a full, clear, and exact description.

Reference is to be had to the accompanying drawings, forming part of this specification, in which similar letters of reference indicate corresponding parts in all the figures.

Figure 1 is a side elevation of a part of a saw-plate illustrating my improvement. Fig. 2 is an edge view of the same. Fig. 3 is a side elevation of a bit-holding spring. Fig. 4 is a side elevation of a bit. Fig. 5 is a front elevation of the same.

The object of this invention is to provide insertible saw-teeth constructed in such a manner that they can be readily inserted and removed without detaching the saw from its mandrel, and without removing the holding-spring from its seat.

The invention consists in the peculiar construction and combination of parts, as will be hereinafter fully described and then claimed.

A represents the saw-plate, in the face of which are formed recesses B to receive the bit-holding springs C and the bits D. The forward end of the recess B is made straight, is inclined to the rearward from a radial line, and is beveled, as shown in Figs. 1 and 2.

In the plate A, at the rear end of the base of the recess B, is formed a projection, E, against which rests a toe, F, formed upon the rear end of the base of the spring C.

In the spring C, between the toe F and the body of the said spring, is formed a slot, G, to give greater elasticity to the said spring.

The saw-plate A at the base of the recess B has a V-shaped edge, to fit into the V-shaped groove in the base of the spring C to hold the said spring from lateral movement in its seat. The rear part of the recess B is curved in the arc of a circle, and in the plate A, at the rear side of the projection E, is formed a recess, H, to receive a projection, I, formed upon the inner part of the rear edge of the bit D.

In the convex rear edge of the bit D is formed a V-shaped groove to receive the V-shaped edge of the plate A at the rear part of the recess B, and in the concave forward edge

of the said bit D is formed a rounded groove to receive the rounded edge of the rear part of the spring C.

In the spring C, opposite the rear corner of the projection E, is formed a recess, J, and in the forward corner of the inner end of the bit D is formed a corresponding recess, K, the two recesses J K forming an aperture to receive a tool for starting the bit D from its seat. After the bit D has been started from its seat the tool is inserted between the inner end of the said bit and the rear side of the projection E and the removal of the bit is completed. The bit D is driven into the seat with a hammer, a socket-block being placed upon the edge of the said bit to protect the said edge from being injured by the blows of the hammer. The spring C is inserted by placing the toe F against the forward side of the projection E and forcing the beveled forward end of the said spring into place against the beveled shoulder of the plate A at the forward end of the recess B by blows with a hammer against the side of the said forward end, the inclination of the said beveled edges forcing the said spring down into its seat. The spring C is removed by blows with a hammer against the other side of its forward end.

Having thus described my invention, I claim as new and desire to secure by Letters Patent—

The combination, with the saw-plate formed with a recess, B, the rear end of which is straight and inclined rearward at one edge, and the bottom of which is made A shape, curved and provided with the projection E between its ends, having a recess, H, in its rear side, of the spring C, having its lower edge and rear end formed to engage the lower edge and the rear end of the recess B, and formed with the rearward-extending slot G, the recess J, and a A-shaped forward end, the bit D, having its sides grooved to engage the A-shaped edges of the spring and recess, the projection I on its lower end fitting into the recess H, and the recess K, forming, in connection with the recess J, a tool-receiving aperture, substantially as set forth.

WILLIAM B. RISDON.
